UNITED STATES PATENT OFFICE.

BRENT C. JACOB, OF CLEVELAND, OHIO, ASSIGNOR TO THE BROWN HOISTING MACHINERY COMPANY, OF CLEVELAND, OHIO, A CORPORATION.

RAIL CLAMP FOR OVERHEAD CRANES.

Application filed November 7, 1922. Serial No. 599,536.

To all whom it may concern:

Be it known that I, BRENT C. JACOB, a citizen of the United States, residing at the city of Cleveland, in the county of Cuyahoga and State of Ohio, have invented a new and useful Improvement in Rail Clamps for Overhead Cranes, of which the following is a sufficiently full, clear, and exact description to enable one skilled in the art to which it relates to make and use the same without other more particular explanation.

The improvement relates or is more plainly applicable to rail clamps or locking mechanism for traveling conveying bridges and the like, and the purpose of the invention is to provide means whereby such structure may be securely fastened or locked to the heads of the rails upon which the bridge structure travels. Means of the kind in question, now used, are mainly of two sorts, namely: a solenoid brake attached to the shaft of the motor that actuates the bridge-travel gear, and rail-clamps that are attached to the pier and shear supporting trucks and which are manipulated either electrically or by hand. Under ordinary conditions the solenoid-brake is sufficiently effective to hold the bridge structure against movement, but, large structures of this type, under the force of the wind, sometimes overcome the resistance by the solenoid brake, and run away.

The main object of my invention may be said to provide a clamping device that will automatically function to clamp the structure to which it pertains, whenever the operator permits, and, when employed on electrically traversed bridges or structures, that may be arranged to unclamp the same in advance of any designed starting of structure, and, that further, under all conditions, by reason of the principle of its construction, will exert a gripping force that depends upon, and is progressively proportioned to the moving force of the mass that is to be resisted and held.

The mechanism hereinafter set forth and more particularly pointed out as embodying the invention, accordingly involves a supporting casing, or frame, from the top of which a pair of oppositely disposed clamp-

ing-arms or members, are pivotally suspended, at such distance apart that their lower, or clamping ends will straddle the rail to be clamped, with their opposing sides in contact, and at right angles with the sides of the rail-head. Said ends, with washer-like blocks or bearings, and other parts, duly shaped for operative contact with each other, are assembled in their proper order on each side of a middle space the width of the rail head, and firmly held in place between the ends of a bolt that is passed through apertures in the frame and the parts for the purpose.

Among the parts so arranged, is a removable wedge-shaped part astride the bolt that is arranged to insert itself between the parts by gravity, when freed for the purpose, and thereby to serve the same locking-function in the alignment, as the key-stone in an arch. In the combination in question, therefore, suitable mechanism for operating this wedge are provided by means of which the locking and unlocking of the series of parts may be effected as occasion requires. The locking-function of the wedge however, as will be obvious, will bring about no greater degree of clamping contact than results from the weight and lateral thrust of the wedge when lowered between the beveled surfaces of the adjoining parts, and, although such degree of clamping will probably be sufficient for ordinary practice, nevertheless, inasmuch as the further aim of the invention, as stated, is to qualify the apparatus for emergency or other extraordinary condition, additional mechanical and structural features are provided to effectuate such end.

These features are the restriction of the movement of one of the pair of clamping-members (that on the left hand in the drawings) to a direction at right angles to its pivotal connection, and the provision for a freely moving joint connection or articulation, and movement, by the other members, and its related parts, measurably aided by certain details with respect to the several contacting parts.

By this arrangement a degree of flexibility is imparted to the device whereby, if,

from any cause, the resistance of the mass clamped exceeds the clamping capacity of the wedge, the jaw of one arm of the pair will remain stationary, against the rail, 5 while that of the other will be carried along the side of the railhead, in a direction parallel to the companion jaw, but on, and against a lengthening radius that will tend progressively to increase the distance between the jaws and, in consequence, will instantly bring about a new and unyielding hold.

The excess moving-force of the structure to be clamped, in this manner is converted 15 from a moving to a braking, or clamping force, for effecting the result sought.

In the accompanying drawings Fig. I is a side view or elevation of a type of traveling conveying-bridge to which this invention is 20 applicable, displaying the relative positions of the rail clamps, controller, and the bridge-travel motor. Fig. II is an enlarged side view of one of the shear-supporting trucks, showing the relation of the rail clamp with 25 the truck and rail head. Fig. III is an enlarged side view of the rail clamp unit, detached from the truck. Fig. IV is an end view of the clamp showing a method of supporting the solenoid unit that is a part 30 of one type of clamp as a whole. Fig. V is a top view of such clamp. Fig. VI is a sectional view of the clamp and solenoid on the lines A—A in Fig. V. Fig VI^a is a view of the clamping element, showing the side 35 adjacent to the rail-head. Fig. VII is a sectional view of the clamp on the lines B—B of Fig. IV, when the clamping element is in gripping engagement with a rail head. Figs. VIII and IX are views at a 40 quadrant interval, of the wedge employed to force the clamping elements into contact with the rail-head. Fig. X is a wiring diagram of an electric system for the control and operation of a bridge-crane equipped 45 with said invention, and Fig. XI is a view similar to Fig. IV showing a means for operating the wedge manually.

Like parts throughout the drawings are 50 designated by the same reference characters.

1 is a traveling conveying bridge-crane as a whole.

2 is the bridge proper which supports the man trolley.

3 is the pier, supporting one end of the bridge.

3^a is one of a pair of trucks that support the pier.

4 is the shear supporting the other end of the bridge.

4^a is one of a pair of trucks that support the shears.

5—5—5 are the rails upon which the pier and shear trucks are mounted; in the construction shown, one rail is required for the shear track and two rails for the pier track.

6 is the man-trolley adapted to traverse the bridge.

7 is the motor-house containing the bridge-traveling gear motor and the contactor panels.

8 is the motor that actuates the bridge-traveling gear 9, shown, in part, in Fig. X.

8^a in Fig. X is the solenoid-brake attached to the shaft of the motor 8.

10 is the master-controller, located on the bridge structure near the shear 3. It may be located also in the man-trolley 6.

11 is the rail clamp as a whole when electrically operated; four of these are usually used on a bridge-crane; two on the shear trucks and two on the pier trucks.

The clamp 11—with its wedge operating solenoid—is made up of several detail pieces. The main or supporting member 11^a is fastened to a truck by means of the bolts 11^b that pass through the holes 11^c and corresponding holes in the truck frame. Said member 11^a is a casting that extends from the lower side of the head 5^a of the rail 5 to be clamped to a height to accommodate the upwardly extending arm 12 of the magnetic frame 13^a of a solenoid 13. A horizontal section of the casting 11^a is much like the letter H; the two vertical sides 11^d and 11^d being connected by the web member 11^e. Bifurcations or cuts 11^f—11^f are made at the bottom of the side members 11^d, 11^d so that the casting 11^a will clear the rail head 5^a. Wing-like portions 11^g—11^g, extend from the side members 11^d, 11^d; these extensions serve as limit stops for one of the swinging clamp-members 14, 14. On the opposite side of the sides 11^d, 11^d are the wing-like extensions 11^h, 11^h which serve as limit stops for the second or left-hand clamp-member 14, and, also as supports for the solenoid 13. Flange portions 11^k, 11^k extend inwardly of the casting 11^a from the extension 11^h, 11^h; these flanges hold the left hand clamp-member 14 (as viewed in the drawings) from any transverse movement.

Swells or protuberances 11^m, 11^m, extending vertically and protruding inwardly from the extensions 11^h, 11^h near their outer edges, are provided with holes 11ⁿ, 11ⁿ, which are the receptacles for solenoid frame supporting springs 16, 16. The holes 11ⁿ, 11ⁿ are of two diameters; the lesser diameter being at the lower portion of the holes, and are a little larger than the springs which the holes accommodate, and the greater diameter extending from the top of the holes downwardly to the lesser diameter. The holes are somewhat larger than the springs to permit the springs to sway when influenced by the action of the solenoid-frame as the solenoid functions.

At the upper left hand corner of the sides 11^d—11^d, are pin holes to accommodate the hinge-pin 15, which extends through the

sides far enough to receive cotters (not shown) in the cotter holes 15^a, 15^a, for holding the pin 15 in the casting 11^a.

At the top of the casting 11^a and extending to the right and left of the web portion 11^e and midway thereof, is a pin-bearing 11^p which holds the swivel-pin 17. The bottom of the web piece 11^e is arched at 11^e to clear a clamping-bolt 18.

10 The swivel-pin 17 has a turned-down portion which fits loosely in the pin-bearing 11^p, and extends through the same a sufficient distance to accommodate a cotter 17^a in the hole 17^b. The enlarged portion of the swivel-pin 17 extends from the face of the pin-bearing 11^p and has a transverse hole to receive a hinge-pin 19. The pin projects from each side of the pin 17 far enough to engage and carry the right-hand clamp-member 14.

15 Cotters (not shown) hold the pin 19 in place.

The configuration of the clamp-members 14, 14 resembles, roughly, a ladle, of which the upper portion is the handle and the lower portion, or jaw, is the bowl. The upper end of handle portion is bifurcated at 14^a (see Fig. VI^a) to a degree to straddle the upwardly extending arm 12 of the solenoid frame in one distance and the swivel-pin 17 in the other. The forked portions of the clamp-member 14 is preferably bent away from the vertical portion and the prong portion 14^c is provided with holes 14^b, to engage the pin 15 in one instance, and the pin 19 in the other.

20 The purpose of bending the forked ends away from the vertical is, to have the center of gravity of the clamps 14—14 at one side of their pivoted points at pins 15 and 19, so that the clamps will automatically swing away from the rail-head 5^a when the solenoid is operated to release the clamps. The handle portion extends downwardly from the pivotal points to a suitable distance to bring the lower edge 14^d of the bowl-portion or jaw in alignment with the rail-head 5^a. The upper half of the bowl, or jaw, is conical in form, and the lower half rectangular, with an aperture of corresponding shape through each portion adapted to receive the bolt 18 therethrough with a free operative clearance for the same.

25 The lower side of the bowl, or jaw, is chamfered around the edge of the aperture, to form a socket-shaped depression or bearing seat 14^e and a flange 14^f projects inwardly from the lower inner face or edge of the jaw to contact with the side of the rail-head when the clamping arms have been compressed towards each other for the purpose.

30 A washer-like piece 20 rounded on one side, or face, to correspond with the socket 14^e and flat on the other side, (to meet and be stopped by the head of the bolt), is provided as a bearing-piece or part for the

right hand clamping-arm 14, and a similar washer 21, having its flat side inclined to the vertical, is provided as a bearing piece, or part for the left hand arm. The spherical surfaces of the washers are preferably described by radii R, R', (Fig. VII) that have their center points at C and C' respectively.

35 The bolt 18, for assembling the parts named in their designed co-relation, is successively passed through apertures or openings in the same for the purpose, from its free, or left hand end, as shown in the drawings, towards the head at the right hand end, namely the washer 20, the open interior of the bowl, or clamping-jaw, of the right hand arm 14, under the arch 11^e, through the bowl of the left-hand arm, the washer 21, a third washer-like piece, or block 23, into a threaded engagement with an adjusting nut 24. Said washer 23 has a face at the same inclination to the axis of its hole as the flat side of the washer 21, and as, in the stated order, the two washers are positioned with their inclined faces opposite to each other, and are slidably mounted on the bolt, it results that there will be an upwardly divergent space or interval between these parts that may be limited to any predetermined width along the bolt, by means of the adjusting nut 24.

40 In actual constructions, this space will always be calculated, as the shape and dimensions, to operatively fit the wedge 22, so that, as occasion requires, when allowed, to wedge will descend by its own weight between said pair of oblique-faced blocks, or washers, and by so doing, force the sliding member of the pair, into an actuating engagement with its next adjacent arm 14, that by the arrangement shown, will bring the pair of arms into the gripping position and contact with the rail-head designed.

45 In such calculation, the precise angle of the wedge, and of the parts on the bolt with which it is to contact, will be governed by various considerations. If small, the weight of the wedge required to set the clamping-jaws against the rail, may be less than if the angle is larger; the wedge will also be more sure of self-locking, and of retaining its locking place against any back-thrust of the parts. A small angle, on the other hand, will necessitate more power, and a larger solenoid, in order to lift the wedge, when the clamps are to be released, and, also, a longer travel to take care of variations in the width of the rail-head.

50 A mortise 25, rectangular in horizontal section, extends downwardly from the top of the wedge and centrally thereof. Pin holes 26, 26, parallel with the shorter sides of the mortise, are located near the top of the wedge and extend from the surface to the mortise.

55 A link 27 whose cross-sectional dimen-

sions are somewhat less than those of the mortise 25, and whose length is sufficient to extend from near the bottom of the mortise 25 in the wedge 22 to near the top of a similar but inverted mortise 28 in the movable core or plunger 13^b to be further pointed out. The lower end is provided with a round hole, which is perpendicular to its flat sides. The pin 30 passes through the holes 26, 26 in the wedge and the hole in the lower end of the link 27 thereby securing the link to the wedge. A second hole 27^a, oblong in shape, extends from near the middle portion of the link 27 to a point near the upper end of the link.

The solenoid 13 is made up of the usual component parts required for electro-magnets, which are: a magnetic frame 13^a, a spool 31 with its conducting wire, a stop or fixed core 13^c and a plunger or movable core 13^b. The magnetic frame 13^a, in which the conducting wire wound on the spool 31 is placed, has its lower cross-piece bored to loosely receive the plunger core 13^b and its upper cross-piece is bored to tightly receive the stop or fixed core 13^c. The stop or fixed core 13^c has two diameters; the top portion, having the greater diameter and fitting tightly into the bore at the top of the magnetic frame 13^a, and is held in place by a bolt 32, and the lower portion with the lesser diameter, extends below the top cross-piece of the frame a short distance into the spool 31, which is bored to the same diameter as the lower cross-piece of the frame 13^a. The stop fits snugly in the spool and holds it in place in the magnet frame. A conical bore extends from the lower face of the stop upwardly to a distance of more than half the length of the stop, the stop being further bored upwardly through its remaining length, to receive the lower end of a plunger-switch 33, that penetrates therethrough into the conical bore below. The plunger or movable core 13^b is of one diameter throughout its cylindrical length and is slightly shorter than the diameters of the spool and the bore in the lower cross-piece of the magnet-frame 13^a, in order that the plunger may function freely. A cone-shaped protuberance 13^d, adapted to fit the conical bore in the stop 13^c, projects from the top of the plunger proper. The mortise 28, above referred to, extends from the bottom of the plunger a sufficient distance upwardly to accommodate a corresponding length of the link 27 that projects upwardly therein from the wedge 22. Near the lower end of the plunger 13^b and at right angles to the long side of the mortise, are holes through which a pin 34 passes. The pin 34 also passes through the slotted hole 27^a in the link 27 when the latter is in place in the mortise 28, thereby completing a loose coupling between the two parts. Holes 35, 35, like the

holes 13^a, 13^a, are located in the bottom of the frame 13^a in alignment with the holes 13^a, 13^a, in the casting 11^a. These holes receive the upper ends of the supporting springs 16, 16. The upwardly extending arm 12 is bifurcated at 12^a and the prongs 12^b, 12^b, of the forked portion straddle the pin 15, which keeps the solenoid in an upright position.

The details of a preferential electrical system comprising in their proper sequence and location, the wiring, resistances, solenoids, terminals, contactors, connections, and other essentials for the functioning of a solenoid-device of the kind shown in the drawings, when an overhead bridge-crane, to which the device pertains, is started, stopped, or continuously traversed upon its supporting rails, are indicated diagrammatically in Fig. X, and, with sufficient definiteness, it is thought, to make it unnecessary to add anything further to the text for a full understanding of the same by those versed in the art.

In that system the positive supply main 41 and the negative supply main 42 comprise the circuit D. The wires of this circuit are strung along the bridge and fed by wires that are led up the pier from the collector shoes on the pier sill.

As will be manifest, when the bridge structure is at a state of rest, the drum of the master controller is at the "off" or neutral position and all the circuits leading to the various switches, contactors, solenoid and the motor are open; the bridge motor brake is set by the spring in the solenoid-brake and the clamping members of the several rail clamps are in engagement with the several rail-heads, and will only be unset, and the rail-clamps drawn clear of the head, when the current that is to travel the bridge has first energized the solenoids 13.

The manually operated clamp 152, shown in Figure XI, is constructed of the same number of clamp details as the electrically operated clamp differentiating therefrom, however, in two details, namely: the clamp casting 152 (corresponding with the casting 11^a) has extensions 152^a, 152^a, at the left of the pin 15 which do not occur on the electrically operated clamp, and, also, in that the wedge 156 (corresponding with 22 in the other figure) is of a different construction above the line 156^a.

The extensions 152^a are provided with holes near their extremities through which a pin 153 is passed for supporting a handle 154, that is bifurcated to receive a curved link 155.

A pin 154^a passes through the prongs of the handle near its pivotal point and through the end of the curved link 155 thereby supporting and connecting the same to the handle. The wedge 156 is of a length

to extend from its place in the clamp to within a short distance of the pin 153. It is connected to the handle 154 by the curved link 155 which enters the space between the 6 prongs at the top end of the wedge. A pin 157 secures the link 155 to the wedge 156.

The clamp is operated to release the clamping members, by throwing the handle 154, from the position shown in full lines, 10 over to the position shown in the dotted lines. The peculiar shape of the link 155 allows its pivotal point on the handle to go beyond the pivotal point 153 of the handle. The relation of the pivotal points 153 and 15 154^a is such, that when the wedge 156 is up and out of engagement, any load or downward pull applied at the point 154 will keep the handle 154 in its uppermost position insuring at all times, when it is desired, a 20 engaged clamp. The manually-operated clamp should be made to engage the rails at the close of a day's work, before the operator leaves the plant. Before again starting the bridge, he should re-visit each clamp 25 and throw the handles over to the upper position.

By the loose-link coupling between the movable core 13^b and in the wedge 22 in the electrically operated device, an interval is 30 insured in the upward plunge of the core when the solenoid 13 is energized, during which the core gains an impetus, or momentum whereby the wedge is disengaged from between the washers 21 and 23, with the exertion of a less pulling force, than if the wedge and plunger-core were in a single piece.

It will be understood that in the means herein shown for practicing the invention, 40 many details are indicated, that, upon due discrimination, will be recognized as contributing, rather to the excellence of form or function than to the essence of the device.

Although the clearance aperture through 45 the lower ends of the clamping arms, for instance, is referred to as conical, it is not intended to thereby restrict the term to its geometrical significance alone, nor, save when distinctly so claimed, to require movable bearing parts, for example, and exclude fixed parts where fixed parts would also express the idea of the invention.

Such dispensable details, it is accordingly expected, will be duly harmonized with idea 55 of the invention as it intended to be claimed.

What is so claimed and sought to be secured by Letters-Patent, is:—

1. A clamping device for securing overhead cranes, and similar structures, to their 60 supporting rails comprising the combination of a casing, oppositely disposed arms pivotally suspended therefrom in a common plane of rotation, one of said members being in a secondary plane of rotation transverse to the common plane, the other arm

being held against movement in that direction; jaws fixed on said arms; inwardly flaring apertures through the jaws; a bolt passing through the apertures; a fixed bearing-part on the bolt on one side of the arms, and 70 a movable bearing-part on the other side, said parts being in suitable alignment to securely engage the arms when moved against the same for the purpose, and having suitable superficial configurations at 75 their points of engagement, to complement suitable configurations provided for the purpose on the arms, and thereby insure flexibility to the engagements effected, together with suitable means, operating on said movable part, for pressing said arms into opposite contact with the rail, and holding the parts contributing to such contact in their relative places, and means for releasing said holding means, and contact, substantially as 80 shown and described.

2. A clamping device for overhead cranes, and similar structures, comprising the combination of a casing, a pair of oppositely related clamping-arms having inwardly flaring apertures therethrough, the members of the pair being suspended from the casing by respectively, a one-way and a two-way pivotal connection; the one-way member being held against movement transversely of such way; a bolt through the apertures; bearing-pieces thereon, at the outer sides of the pairs, adapted to engage the jaws oppositely, when moved towards each other along the bolt, one of said pieces being slidably mounted on the bolt and the other fixedly held against outward movement thereon by a stop, or head, on the bolt provided for the purpose, and suitable means, operating on said bearing-pieces, for forcing the jaws towards and into contact with the rail to be clamped, and, holding such contact until released, together with means for releasing the same, substantially as shown and 95 described.

3. A clamping-device for overhead cranes, and similar structures, comprising the combination of a casing, a pair of oppositely related clamping-arms having jaws with inwardly flaring apertures therethrough, fixed to the same, the members of the pair being suspended from the casing by, respectively, a one-way and a two-way pivotal connection, the one-way member being held by the casing against movement transversely to such way; a bolt, provided with closure-ends, passing through the apertures; oppositely arranged bearing pieces on the bolt, at the outer side of the pair, in engagement, severally, with the jaws, said bearing pieces and said jaws being complementary in contour at their points of engagement, and one of the bearing-pieces being movable along the bolt, and having its further side sloping; 125 a third bearing-piece, with its near side 130

sloping at a corresponding angle, on the bolt at a predetermined distance from the movable piece, and a wedge, of approximately the dimensions and shape of the 5 space between the sloping pieces when such members are in their designed co-operating places within said space, together with suitable means for lifting the wedge therefrom, and for permitting it to descend therein, ac- 10 cording as it is desired to release the jaws from their clamping contact with the rail, or force them into such contact, said closure- pieces on the bolt being at such pre-determined distance apart, and said bearing- 15 pieces and jaws of such dimensions and shapes, that when the jaws are in clamping contact with the rail and said wedge within said space, said bearing-pieces, jaws and wedge will be closely held together against 20 the closure-pieces throughout said distance between, substantially as shown and described.

4. A device for clamping electrically traveled overhead cranes, and similar structures, 25 to their supporting rails, comprising the combination of a casing, a pair of oppositely disposed clamping-arms having jaws with inwardly flaring apertures therethrough, the members of the pair being pivotally sus- 30 pended from the casing by, respectively, a one-way and a two-way pivotal connection, the one-way member being held by the cas- ing against movement transversely to such way; a bolt, provided with closure ends, 35 passing through the apertures, oppositely

arranged bearing-pieces on the bolt, at the outer sides of the pair in engagement, severally, with the jaws, said bearing-pieces and said jaws being complementary in contour at the points of bearing engagement 40 to add flexibility thereto, and one of the bearing-pieces being movable along the bolt, and having its further side sloping; a third bearing-piece, with its near side sloping at a corresponding angle, on the bolt located at 45 a predetermined distance from the movable piece when said piece is at the limit of its inward movement along the bolt; a wedge of approximately the dimensions and shape of the space between said sloping pieces 50 when said pieces are at the limit of their opposite movements along the bolt; a solenoid operatively connected to the wedge for lifting the same above said space when electrically energized, and releasing the same from 55 such position when de-energized, the closure-pieces at the bolt ends being at such pre-determined distance apart, and said bearing pieces and jaws of such dimensions and shapes, that when the jaws are in clamping 60 contact with the rail, and said wedge within said space, the bearing-pieces, jaws and wedge will be closely held together against the closure-pieces throughout the entire distance between.

BRENT C. JACOB.
